ATTORNEY.

UNITED STATES PATENT OFFICE.

ALMERON FENNER, OF SYRACUSE, NEW YORK.

WEATHER-STRIP.

No. 918,836.

Specification of Letters Patent.

Patented April 20, 1909.

Application filed July 25, 1908. Serial No. 445,834.

To all whom it may concern:

Be it known that I, ALMERON FENNER, a citizen of the United States, residing at Syracuse, in the county of Onondaga and State of 5 New York, have invented certain new and useful Improvements in Weather-Strips, of which the following is a specification.

This invention relates to improvements in weather strips, designed for use in connection with the doors of dwellings and like 10 structures.

The invention relates particularly to improvements in the device shown and described in Letters Patent of the U. S. 15 granted to Allen H. Cole and George R. Menin, No. 536,919, and bearing date April 2, 1895, the object being to provide a weather strip which is more positive in its operation, and also to render the same more 20 effective in fulfilling its office.

A further object is to provide means for adjusting certain parts of the device.

Other features and objects of the invention will be understood from the detail description 25 which follows, and by reference to the accompanying drawing which forms a part of this specification, and in which—

Figure 1 is an elevation of the lower portion of a door frame and door, having my 30 improved weather strip attached, the door being closed. Fig. 2 is a vertical section on line 2—2 of Fig. 1, showing the position of the strip when the door is closed. Fig. 3 is a view similar to Fig. 2, showing the position 35 of the threshold strip when the door is open. Fig. 4 is an enlarged plan view of the threshold strip. Fig. 5 is a similar view, showing the manner of applying the adjustable hanger lugs; also showing trip-arms mounted upon 40 the opposite ends of the strip ready for service. Fig. 6 is an enlarged detail end view of the double angular strip carried by the door.

In the several views like characters of reference 45 designate corresponding parts.

In the drawing, 2 represents a door frame and 3 the door. The weather strip, or that portion of the device which is attached to the door frame and disposed adjacent to the sill, 50 consists of a metallic bar 4 provided at its opposite ends and adjacent to its outer edge with upwardly inclined hanger lugs 5, preferably made of metal and adjustably attached to the ends of the bar 4, by means of slots 6, 55 and rivets or bolts 7. To facilitate attaching the lugs 5 to the bar 4, the latter is provided

with circular perforations 8 at one end, the opposite end being slotted as at 9, to receive the rivets 7 after they have passed through the slots of lugs 5. In order to attach the 60 threshold strip 2 to the frame of the door, in a manner to allow the same to be tilted or shifted to different positions, as indicated in Figs. 1, 2 and 3, the upturned portion of the lugs 5 are pierced by elongated slots 10, 65 through which screws or pins 11 are passed into the door frame to provide a varying pivotal support for the strip 4. This variable center or pivot is made necessary for the reason that a constant or fixed center would 70 prevent the tilting of the strip from the position illustrated in Fig. 3, which indicates the position of the strip when not in use, to the position shown in Fig. 2, which indicates the operative position of the strip, as when the 75 door is closed.

12 and 13 represent a pair of angular metallic plates or strips connected together, at their upper edges by rivets 14, or may be welded to form one part. These plates are 80 secured to the lower end of the door, by screws or other suitable means, in position to engage the strip 4 when the door is closed, for the purpose of making a close seal of the crevice beneath the door. The bent strips 85 12 and 13 are preferably formed to different angles as shown in Figs. 2 and 6, their lower edges being spaced apart sufficiently to receive the inner edge of the plate 4 when the door is closed, as shown in Fig. 2. In 90 the former patent referred to, a single bent plate, as 12, was employed, and under the old construction, when the weather strip was applied to a door of ordinary width, the threshold plate showed a tendency to sag 95 for the greater part of its length, and left a gap between the two plates (4 and 12) through which the wind, rain and snow could pass. In the present application an additional angular plate 13 is provided, for 100 the purpose of holding the strip 4 for its entire length tightly against the under side of the plate 12, and thus prevent the sagging of the strip. 15 and 16 indicate 105 respectively, a trip-arm and a supporting arm which are rigidly mounted at or near the ends and upon the upper or face side of the strip 4, as shown in Figs. 1 and 5. These arms are disposed in position to be engaged by the bent strip 12 when the door is closed, 110 and by means of the arm 15 the strip 4 is raised up from the idle position shown in

Fig. 3, to and held snugly against the rear side of the plate 12, as shown in Fig. 2. Heretofore, weather strips of this class were provided with a trip-arm which was attached 5 to one end of the threshold strip 4, generally at the lock side of the door, in a manner to be engaged by the bent strip during the final closing movement of the door. Under this construction and arrangement the entire 10 weight and strain of the threshold strip, when in the inclined or service position, as shown in Fig. 2, depended for its raising and support upon the single trip-arm disposed at one end of the strip, with the result that 15 the opposite end of the strip would gravitate or sag away from the bent plate and leave an opening for the passage of air &c., between the strips. In order to overcome this defect, I have provided the two arms 20 15 and 16, one for each end of the threshold strip, as shown in the drawing. The trip-arm 15 which is disposed at the hinge side of the door, is preferably made longer and heavier than the trip 16, it being subjected 25 to a greater and more constant strain, for the reason that it is in engagement with plate 12, during the greater part of the opening and closing movements of the door, while the arm 16 is not engaged until the 30 door is practically closed when it coacts to support the parts 4, 12, and 13 in close contact; it is disengaged upon the first slight opening movement of the door. The arms 35 15 and 16 are secured in rigid manner to the strip 4 by the rivets or bolts 7. After the parts of the weather strip are placed in operative position, at each closing movement of the door, strip 4 is picked up and enters and lies between plates 12 and 13 40 practically the same as a jack-knife blade fits into the handle.

At the time the strips 4 are made, duplicate perforations 8 are formed near one end of the strips and duplicate slots 9 are formed 45 in the opposite ends. The object of this feature is to provide for cutting off the strips to suitable lengths for applying to door frames of different widths. In practice the strips 4 and also plates 12 and 13 50 are made in three or four standard lengths, calculating for applying to the widest and narrowest door ways, and as the widths of door frames vary considerably, the strips 4 may afterward be cut as on either the line 55 a—a, or line x—x, or on both of said lines as shown in Fig. 4, and these may be fitted into any of the intermediate widths of frames. The angle plates 12 and 13 must be cut to correspond to the length of strip 4. 60 After the strips have been cut to suitable lengths, the hanger lugs and arms are placed in position and properly adjusted and then permanently secured by the rivets or bolts 7.

When the door is opened sufficiently to 65 disengage the bent strip 12 from the arms

15 and 16, the weight of the strip 4 causes it to drop toward the threshold, and by reason of the transverse slots 6 in the lugs 5, through which the pins 11 pass, the center or rotation changes so that said strip may 70 lie flat thereon, as shown in Fig. 3.

Having thus described my invention, what I claim as new and desire to secure by Letters Patent, is—

1. The combination with a door and a 75 door frame, of a weather strip mounted in said frame and capable of being tilted, a trip-arm projecting from said strip, and plates secured to the door and having spaced edge portions adapted to receive therebetween 80 the edge of the weather strip aforesaid, the upper of said plates being arranged to engage the trip-arm to tilt the weather strip into operative position, and the lower of said plates being in close contact throughout its 85 length with the weather strip when the latter is received between the plates.

2. The combination with a door and a 90 door frame, of a weather strip mounted on the door frame and tiltable into operative 95 position, plates secured to the door and having spaced edges between which the edge portion of the weather strip is adapted to be received and to lie in close contact with said plates throughout the length thereof, and means for tilting and supporting the weather strip to cause co-operation thereof with the plates on the door, said means comprising a trip-arm secured to the weather strip at the end adjacent to the hinged edge of the door, 100 and a supporting arm secured to the weather strip at the opposite end thereof, both the trip and supporting arms being engaged with the upper plate on the door when the weather strip is in operative position.

3. The combination with a door and a 105 door frame, of a weather strip mounted transversely in the door frame above the sill thereof, hanger lugs adjustably connected with the opposite ends of the weather strip 110 and apertured for pivotal connection with the door frame, a trip-arm secured to one of the hanger lugs, a supporting arm secured to the other hanger lug, and means carried by the door for throwing the weather strip into operative position when the door closes, said means co-acting with the trip and supporting arms aforesaid.

4. The combination with a door and a 115 door frame, of a weather strip pivotally mounted in the door frame between the sides thereof, a trip-arm projecting laterally from the weather strip and having an inclined end located adjacent to the hinged edge of the door, a similarly arranged supporting arm at 120 the opposite end of the weather strip and adjacent to the locking edge of the door, a pair of plates secured to the door so that the upper edges thereof are in close contact while the lower portions extend from the upper 130

portions at different angles and are thus spaced apart, the uppermost of said plates being adapted for initial engagement with the trip-arm as the door closes and final engagement with the supporting arm when the door is closed, the initial engagement with the trip-arm raising the weather strip into operative position and the final engagement with the supporting arm supporting the strip 10 at the locking edge of the door, the lower

plate resting in intimate contact throughout its length with the weather strip when the door is in closed position.

In testimony whereof I affix my signature in presence of two witnesses.

ALMERON FENNER.
